UNITED STATES PATENT OFFICE

CLARENCE J. LEMONT, OF SOUTH MILWAUKEE, WISCONSIN, ASSIGNOR TO LINE MATERIAL COMPANY, OF SOUTH MILWAUKEE, WISCONSIN, A CORPORATION OF DELAWARE

SUPPORTING FIXTURE

Application filed March 15, 1930. Serial No. 436,106.

This invention relates to certain new and useful improvements in supporting fixtures and refers more particularly to a secondary rack for carrying secondary wires along poles or other places.

It is an object of this invention to generally improve and simplify the construction of racks of the character described.

A further object of this invention is to provide an improved insulator carrying rack formed from stampings to reduce the cost of production.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, the single perspective view, with parts broken away and in section, illustrates one complete example of the physical embodiment of my invention constructed according to the best mode I have so far devised for the practical application thereof.

My improved rack comprises a vertical support or member 5 of channeled construction having side flanges 6 connected by a transverse web or front portion 7 which is slotted at intervals, as at 8, to receive lag screws or other attaching means 9. One or more pairs of rectangular openings are also formed in the transverse web portion, to receive the inner ends of lateral arms 12 for mounting insulators 13.

Each arm 12 is pressed from a single piece of metal and has a substantially rectangular tubular cross-section, one side thereof being formed by the abutting portions 14 and the opposite side 14' being in one piece. The side pieces 14 and 14' are cut away at their inner ends leaving the adjacent ends of the top and bottom portions 15 extended therebeyond. The extended ends of the top and bottom portions of each arm 12 are projected through its respective opening 10 and are di-

rected laterally as at 16 to overlie the inner face of the transverse web 7, to which they are secured by rivets or other means 17. The width of the extended ends 16 being slightly less than that of the top and bottom portions 15, forms shoulders 18 which abut the outer face of the vertical member 5 and thus restrain lateral movement of the arms 12.

The openings 10 of each pair are spaced a distance substantially equal to the height of the insulator spool 13 which is mounted between the lateral arms by a bolt or pin 10 adapted to be detachably secured in place by a cotter pin 20. As will be apparent, any number of pairs of lateral arms 12 may be provided and if desired, in lieu of independent or separate pins or bolts 19 for each insulator, a single bolt passing through the outer ends of the lateral arms 12 may be provided.

This application is a continuance in part of application Serial No. 31,114, filed May 18, 1925.

From the foregoing description taken in connection with the accompanying drawing it will be readily obvious to those skilled in the art to which an invention of this character appertains, that I provide an insulator supporting fixture or secondary rack which is of extremely simple construction, is strongly constructed and which may be made of any size to accommodate any desired number of insulators.

What I claim as my invention is:

1. An insulator supporting fixture, comprising a main member having a rectangular opening therein, an insulator carrying member of rectangular shape in cross-section at its inner end, a shoulder at the inner end of said rectangular shaped end of the lateral member and adapted to abut the outer face of the main member, tongues on the extreme end of said rectangular shaped portion of the lateral member and adapted to be bent after insertion through the main member opening to engage the inner face thereof and secure the lateral member in position, and securing means passed through the tongues and the main member.

2. An insulator support comprising a ver-

- tical member of channeled construction having a rectangular opening in its front face, a lateral member substantially rectangular in cross-section, shoulders formed by cutting away a pair of opposite sides of the lateral member adjacent its inner end, and tongues extended from the other opposite sides of the lateral member, said tongues being of a width less than the width of the lateral member and of a width substantially equal to that of the rectangular opening and being adapted to be passed therethrough and directed laterally to hold the shoulder against the vertical member.
15. 3. An insulator support comprising a vertical channel member having a rectangular opening in its face, a lateral member formed of a single piece of sheet metal and substantially rectangular in cross-section, shoulders formed at the inner ends of the lateral member and abutting said face, and tongues extended from said member and adapted to be passed through the opening and directed laterally to secure the lateral member to the face of the vertical member.
20. 4. An insulator support, comprising a longitudinal channel member having a rectangular opening in its face, a lateral member formed of a single piece of sheet metal and substantially rectangular in cross-section, shoulders formed at opposite sides of the lateral member adjacent its inner end, tongues extended from the other opposite sides of the inner end of the lateral member, said tongues being of a width less than the width of the lateral member and substantially equal to the width of the rectangular opening through which they are passed and directed laterally to engage the inner face of the channel member and hold the shoulders against the outer face thereof, and rivets passed through the face of the channel member and the tongues.
25. 5. In an insulator support comprising a vertical channel member having a rectangular opening in its face, a lateral member of substantially rectangular cross-section and having two parallel edges projecting beyond the outer end thereof, shoulders formed at the inner ends of the lateral member and tongues extending from said member and directed laterally to secure the lateral member to the face of the vertical member.

In testimony whereof I have hereunto affixed my signature.

CLARENCE J. LEMONT.
